PUZZLE

John D. Boyle, Greenwich, Conn.

Application August 30, 1939, Serial No. 292,552

8 Claims. (Cl. 273—156)

The invention herein disclosed relates to puzzles of the take-apart type.

Objects of the invention are to provide an attractive form of puzzle, presenting an interesting problem as to separation of the same into its unit parts and which can be produced at low cost in readily available materials.

Further objects and the novel features of the invention will appear as the specification proceeds.

The drawing accompanying and forming part of the specification illustrates one of the practical commercial embodiments of the invention. The structure, however, may be modified and changed as regards this disclosure, all within the true intent and broad scope of the invention as hereinafter defined and claimed.

Figure 1 is a front elevation of one of the puzzles.

Figure 2 is an edge view of the same.

Figure 3 is a front view illustrating the action of releasing parts.

Figure 4 is a side or edge view of the intermediate member for holding the parts together.

In the particular form of the invention illustrated the puzzle consists of three circular disk-like blocks 5, 6, 7, an intermediate holder or tie element 8 and a series of three pin tumblers 9, 10, 11, sliding in passages in the blocks and extending through openings 12 registering with such passages, in the three triangularly related arms 13 of the tie member.

The tumbler passages in the blocks are all alike, consisting in each instance of two convergent bores 14 entered through the side of each block and having closed inner ends 15 limiting inward travel of the tumblers.

In the present disclosure, tumbler 11, as indicated in Figure 1, is shorter than the other two, tumbler 10 is shorter than tumbler 9 and the latter has a notch 16 in the side of the same at one end and which, when in register with the end of tumbler 10, will permit the latter sufficient travel, Figure 3, to clear the end of short tumbler 11.

By rotative twisting movements of disk 6 on tumbler 9 the latter may be worked around to a position where notch 16 in the end of the same will register with the end of plunger 10. By rocking the puzzle as a whole the plunger 10 may then be tumbled into notch 16. By continuation of such rocking movements plunger 11 may then be tumbled the full distance into its bore 14 in disk 7. When this relation of the parts is attained, as indicated in Figure 3, disk 5 may be twisted on plunger 9 to carry the bore 14, in which

the end of the short plunger is seated, clear of that plunger, thus to unlock disk 5 from the position in which it is ordinarily held by retainer 8.

The parts can be reassembled and locked by reverse operations.

As an added feature of interest, a coin, good luck symbol or other article 17 may be seated in a slot 18 in the edge of one of the members normally opposed to a portion 19 of the retainer, so that said coin or other element will not be released until the disk carrying the same is released from the retainer, or to an extent such as that indicated in Figure 3, where the retainer no longer closes the end of the slot.

One or a number of such coins or emblems 18 may be seated in the puzzle, secured in such relation so long as the puzzle remains intact or in the locked state. Such retained element or elements may be seated in the retainer, to be released only when uncovered by removal of one 20 or more of the disk elements.

In the present illustration, the retainer is in the form of a three armed stamping of sheet material, which arms are perforated and twisted from the general flat plane of the central portion 25 so as to bring the arms carrying the openings 12 substantially at right angles to the axes of the three tumblers.

The several parts of the device may be made of wood, plastic, metal or other materials and may 30 be colored and ornamented in various ways. The number and shape of the parts may vary. Thus, the block numbers may be spherical instead of flat circular form or they may be of various angular shapes. The retainer in the form shown 35 is in the nature of an intermediate connecting frame or spider and may be so considered.

What is claimed is:

1. A take-apart puzzle, comprising a number of block members, a retainer having portions interposed between said block members, tumblers slidingly seated in said block members, said block members and retainer having registering passages in which said tumblers are operable, the passages in each block member intersecting to 45 enable the end of a tumbler in one such passage to block the movement of a tumbler in the adjoining intersecting passage and one of the tumblers being of a length and having movement when unblocked by an adjoining tumbler sufficient to release one of the block members.

2. A take-apart puzzle, comprising a number of block members, a retainer having portions interposed between said block members, tumblers slidingly seated in said block members, said block 55

- members and retainer having registering passages in which said tumblers are operable, the passages in each block member intersecting to enable the end of a tumbler in one such passage to block the movement of a tumbler in the adjoining intersecting passage and one of the tumblers being of a length and having movement when unblocked by an adjoining tumbler sufficient to release one of the block members, said 5 tumbler being shorter than the other tumblers and one of said other tumblers being rotatable and having a notch in one side of the same which by rotation of said tumbler can be opposed to the end of the adjoining tumbler.
- 10 3. A take-apart puzzle, comprising a number of block members, a retainer having portions interposed between said block members, tumblers slidingly seated in said block members, said block members and retainer having registering passages in which said tumblers are operable, the 15 passages in each block member intersecting to enable the end of a tumbler in one such passage to block the movement of a tumbler in the adjoining intersecting passage and one of the tumblers being of a length and having movement when unblocked by an adjoining tumbler sufficient to release one of the block members, one of 20 said block members having an open slot opposed to a portion of the retainer and a loose member releasably held in said slot by said retainer.
- 25 4. A triangular take-apart puzzle, comprising three disks having convergent passages extending in through the sides of the same and registering 25 end to end with the disks disposed in triangular relation, a triangular retainer having arms extending between adjacent disks with openings therethrough in line with said registering passages and tumblers in said passages extending 30 through said openings, said tumblers being disposed to block and to release the ends of adjoining tumblers and one of said tumblers having a possible endwise movement sufficient to release the disk normally held thereby.
- 35 5. A take-apart puzzle, comprising a number of block members, a retainer having portions interposed between said block members, tumblers slidingly seated in said block members, said block members and retainer having registering passages in which said tumblers are operable, the 40 passages in each block member intersecting to enable the end of a tumbler in one such passage to block the movement of a tumbler in the adjoining intersecting passage and one of the tum-

blers being of a length and having movement when unblocked by an adjoining tumbler sufficient to release one of the block members and a member releasably held between one of said block members and retainer.

6. A take-apart puzzle, comprising a number of block members, a retainer having portions interposed between said block members, tumblers slidingly seated in said block members, said block members and retainer having registering passages in which said tumblers are operable, the 10 passages in each block member intersecting to enable the end of a tumbler in one such passage to block the movement of a tumbler in the adjoining intersecting passage and one of the tumblers being of a length and having movement when unblocked by an adjoining tumbler sufficient to release one of the block members, one of 15 said block members having an open slot opposed to a portion of the retainer and a loose member 20 releasably held in said slot by said retainer.

7. A take-apart puzzle, comprising a retainer having angularly related arms provided with openings therethrough, separable elements disposed in the angles between said arms and having 25 passages registering with said openings in the retainer arms, said passages meeting convergently in said elements and sliding pin tumblers disposed in said passages and extending through 30 said openings in the retainer arms, said tumblers being of a length for the inner ends of adjoining tumblers in the intersecting passages to cooperate as stops in certain positions of the tumblers and one tumbler being reduced to permit tumbler movement sufficient for release of one of the 35 elements.

8. A take-apart puzzle, comprising a retainer having angularly related arms provided with openings therethrough, separable elements disposed in the angles between said arms and having 40 passages registering with said openings in the retainer arms, said passages meeting convergently in said elements and sliding pin tumblers disposed in said passages and extending through 45 said openings in the retainer arms, said tumblers being of a length for the inner ends of adjoining tumblers in the intersecting passages to cooperate as stops in certain positions of the tumblers and one tumbler being reduced to permit tumbler movement sufficient for release of one 50 of the elements and the reduction of said tumbler being provided by a notch in the side at one end of the tumbler.

JOHN D. BOYLE.
